UNITED STATES PATENT OFFICE.

ALFRED E. STAFFORD, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING LOOM.

Application filed March 31, 1923. Serial No. 628,123.

To all whom it may concern:

Be it known that I, ALFRED E. STAFFORD, a citizen of the United States, residing at Hopedale, in the county of Worcester and State of Massachusetts, have invented an Improvement in Filling-Replenishing Looms, of which the following description, in connection with the accompanying drawings, is a specification, like characters on the drawings representing like parts.

This invention relates to filling replenishing looms and more particularly to the shuttle feeler of such looms.

In looms of the automatic type wherein the filling in the shuttle is replenished from time to time, it is necessary that the shuttle to be replenished shall be properly positioned in the replenishing shuttle box to permit the proper transfer of the filling thereto. Should the shuttle be not properly boxed and the replenishing mechanism be operated, injury or breakage of some parts would occur. To avoid this objectionable condition it is common to provide a shuttle feeler in looms of the replenishing type, the function of which is to feel for the shuttle when the filling is to be changed, and in case the shuttle is not properly boxed, to suspend the operation of the replenishing mechanism.

It has been common heretofore to provide shuttle feelers of various forms, some of which have had a recessed shuttle-feeling end, and in some cases thread cutting mechanism. In such cases, when the shuttle feeler is moved rearwardly to shuttle feeling position, and finds an improperly boxed shuttle, the filling or weft leading from the shuttle to the cloth selvage is liable to be caught between the engaging portions of the shuttle feeler and the shuttle and consequently be broken or cut. Should this occur and the shuttle be picked without replenishment, filling would fail to be laid properly in the shed and imperfect cloth would result.

One of the objects of the present invention, therefore, is to provide a shuttle feeler with a weft or filling displacer of such construction that when the shuttle feeler is moved rearwardly into shuttle feeling position, the weft or filling displacer will engage and displace or move the weft or filling from its normal position and from between the engaging surfaces of the shuttle

feeler and shuttle, so that all danger of the filling being cut or broken between the engaging surfaces of the shuttle feeler and shuttle is avoided.

It frequently happens that, even though the shuttle be boxed in such position that the replenishing mechanism may effectively operate, the sharp metallic end of the shuttle will rub along the adjacent surface of the shuttle feeler as the latter moves to its rearward position. In such cases, also, in accordance with the present invention, the weft or filling displacer will displace the weft or filling thread and cause it to ride about the curved contoured end portion of the shuttle out of the danger zone. This recurring contact between the extreme end of the shuttle and the shuttle feeler eventually wears the shuttle feeler, so that it may no longer perform its shuttle feeling function properly, and a new feeler has to be substituted.

A further purpose of the present invention, therefore, is to provide a shuttle feeler with a shuttle feeling end portion which is detachably and adjustably secured to the body portion of the feeler, so that when the shuttle feeling end of the feeler becomes unduly worn, it may be readily replaced by a new tip or end portion without the substitution of the entire feeler.

The above features and other novel constructions and combinations of parts will be hereinafter described in connection with the accompanying drawings which show one good practical form of the invention.

In the drawings:

Fig. 1 is a perspective view from near the front center of a filling replenishing loom looking towards the replenishing shuttle box, the shuttle feeler being shown as moving towards its shuttle feeling position;

Fig. 2 is an enlarged end view of the shuttle and the shuttle engaging end of the shuttle feeler, showing the weft or filling displacer as having lifted or displaced the weft or filling thread from between the engaging surfaces of the shuttle feeler and shuttle;

Fig. 3 is an enlarged perspective view showing more particularly the action of the weft or filling displacer as the feeler moves fully to its rearward position when the shuttle is properly boxed;

Fig. 4 is a detail showing by full and

dotted lines the lateral adjustability of the shuttle engaging end portion of the feeler.

The filling replenishing loom may be of any usual type where the filling is automatically replenished in the shuttle without stopping the loom, but in the present instance the loom is shown of the automatic Northrop type, wherein wound filling carriers or bobbins are held in a hopper and 10 are transferred to the shuttle as occasion requires.

The loom frame 1 may be of usual construction having extending upwardly from the end of the breast beam 2 the filling replenishing stand 3 carrying the usual hopper for supporting the wound filling carriers or bobbins. The details of the replenishing mechanism and the means of rotating the hopper from time to time to present a filling 20 carrier for transfer are all well understood and are consequently not herein shown and described, because the details thereof form no part of the present invention.

The lay 4 has the usual shuttle boxes, one 25 at each side of the loom, only the filling replenishing shuttle box 5 being indicated in the present drawings.

In looms of the filling replenishing type, the shuttle feeler is moved from a front to a 30 rear position when a change or replenishment of filling is called, and various forms of mechanisms have been devised for this purpose which act to suspend the filling replenishing operation should the shuttle feeler 35 find an improperly boxed shuttle in the shuttle box. In the present instance of the invention, the shuttle feeler 6 is mounted on a stud 7 projecting from the rearward extending portion 8 by a bracket 9 secured by bolts 40 10 to the loom frame, and is given its rearward movement when the filling is to be changed, from a train of mechanism actuated from the transverse shaft 11. The transverse shaft 11 is supported for rocking 45 movement in the bearings 12, one at each side of the loom, and secured to the transverse shaft 11 is the arm 13 the rearwardly extending portion 14 of which overlies a stud 15 projecting from the feeler 6. Mounted 50 upon the arm 14 is the yielding member 16 normally under the influence of a spring 17 tending to turn the arm 14 and transverse shaft 11 in a contra-clockwise direction. The yielding member 16 has a rearwardly 55 extending finger 18 which underlies the stud or pin 15, the construction being such that on call for replenishment of filling, the arms 14 and yielding member 16 act to yieldingly move the shuttle feeler to its rearward feeling position.

The feeler 6 extends upwardly from its pivotal support 7 and at its upper portion has adjustably secured thereto the shuttle engaging portion 19. In the present instance of the invention, the body portion of

the shuttle feeler 6 is provided with a shoulder 20, Fig. 3, against which rests the forward end portion 21 of the shuttle engaging member 19 which is secured to the body portion of the feeler by the bolt 22, the construction being such that should the shuttle engaging end portion of the feeler become unduly worn, it may be replaced by manipulation of the bolt 22 and a new end portion be substituted therefor without the necessity 75 of disassembling the loom by the removal of the entire shuttle feeler.

The end portion of the shuttle 23 tapers toward the end and has a rounded contour which terminates in the metal tip 24. When 80 filling replenishment is called and the shuttle feeler moves to perform its shuttle feeling function the end portion 19 moves rearwardly, and if the shuttle is properly boxed, passes beyond the metal tip 24 of the shuttle. In case the side face of the shuttle feeling portion 19 of the feeler rubs along the metal tip 24 of the shuttle as it moves to the position indicated in Fig. 3, the filling thread 85 α is liable to be caught between the two surfaces and be broken or cut. Similarly, should the shuttle be improperly boxed, or have rebounded, and not be in position for filling transfer, the rear end portion of the feeler will engage the end of the shuttle 90 and be arrested in its backward movement. The normal position of the weft or filling is such that the thread is liable to be caught between the engaging surfaces of the shuttle and shuttle feeler and be cut or broken, so that on the following pick no filling will be 95 laid in the shed.

In accordance with the present invention, the shuttle engaging end portion of the feeler is provided with a weft or filling displacer 25, shown in the present instance as formed by the intersection of the relatively long, also inclined, surface 26, and the relatively shorter inclined surface 27, which intersect at 28 at a point above the longitudinal axis of the shuttle 23, when the latter is 100 in the filling replenishing box.

When the shuttle feeler is moved to its rearward feeling position, the weft or filling thread α is first engaged by the weft or filling displacer and, in the present instance, is raised or lifted above the longitudinal axis 105 of the shuttle. If, at such times, the shuttle is properly boxed, the weft or filling thread α will be carried upwardly over the rounded surface of the end of the shuttle, as indicated in Fig. 3, and consequently be removed from danger of being cut or broken as the shuttle feeler moves to its full feeling position. If, on the other hand, the shuttle is 110 improperly boxed, or has rebounded, as indicated in Figs. 1 and 2, the weft or filling thread α will again be engaged by the weft or filling displacer, and lifted into the position indicated in Fig. 2, so that as the in- 115

clined surface 26 meets the rounded surface of the shuttle at the portion 30, the weft or filling thread will have been moved out of the danger zone and consequently not be 5 cut or broken, so that on the following pick, filling will be laid in the shed.

It is sometimes desirable to laterally adjust the shuttle engaging end portion of the 10 feeler and to this end the part 19 of the feeler, in the present instance, is provided with the ribs or projections 31 which are separated by a space 32 and the bolt 22 passes between the two ribs or projections 31. As the result, the shuttle engaging portion 15 19 of the feeler may be adjusted laterally with respect to the main body of the feeler by varying the height of the ribs or projections 31. This adjustability of the shuttle engaging portion of the feeler is 20 indicated by dotted and full lines in Fig. 4, and as will be obvious, serves to enable the shuttle engaging end portion of the feeler to be continued in use for some time, even after it becomes worn.

25 In some forms of shuttle feeler mechanisms heretofore devised, the feeler has been moved in an inclined path rearwardly towards the shuttle box and then returned in a reverse inclined path towards the front 30 of the loom. A slotted guide has been used heretofore to direct the lateral movement of the shuttle feeler. In the present instance, however, the shuttle feeler moves in a path that is not inclined but extends directly fore and aft of the loom. Nevertheless, when an end of an improperly boxed shuttle is engaged by the feeler, the rounded inclined end portion of the engaged shuttle places side or lateral stress on the feeler 35 and tends to deflect it laterally to the left, in the present instance. In accordance with the present invention, therefore, the bracket 9 is provided with a stationary brace portion 33, Fig. 1, along which the body portion 40 of the feeler moves, and by which the feeler is braced against lateral stress as the feeler is moved to its rearward feeling position.

What is claimed is:

45 1. In a filling replenishing loom, the combination of the lay and shuttle boxes, a shuttle feeler having a weft or filling displacing end formed by two inclined surfaces of unequal length which provide a weft or filling seat at their intersection which is above the longitudinal axis of the shuttle when

the feeler is moved to shuttle-feeling position, that the weft or filling thread may be displaced to a position away from the engaging portions of the shuttle feeler and 50 shuttle and not be cut when the shuttle feeler moves to feeling position and encounters and the end portion of an improperly boxed shuttle.

2. In a filling replenishing loom, the combination of the lay and shuttle boxes, a shuttle feeler having a weft or filling displacing end comprising two inclined surfaces of unequal length intersecting to form a notch which is above the longitudinal 70 axis of the shuttle when the feeler is in feeling position, and means for moving the feeler to feeling position to upwardly displace the weft or filling from its normal position and rearwardly over the end of the 75 shuttle that it may not be cut by engaging portions of the shuttle feeler and shuttle.

3. In a filling replenishing loom, the combination of the lay and shuttle-boxes, a shuttle feeler having its shuttle-feeling portion 80 provided with a weft or filling displacer which moves the weft or filling over the rounded and tapering end of the shuttle away from the longitudinal axis thereof and from between the engaging portions of the 85 shuttle feeler and shuttle that it may not be cut when the shuttle feeler moves to feeling position and engages an improperly boxed shuttle.

4. A shuttle feeler comprising a main 90 body portion, a separate shuttle engaging end portion, means for detachably connecting the two portions, and two ribs in separated relation between the main body portion and the shuttle engaging end portion 95 which enable the shuttle engaging end portion of the shuttle feeler to be laterally adjusted.

5. A shuttle feeler having its shuttle engaging end formed with a weft or filling 100 displacer comprising a relatively long lower inclined surface and a relatively short upper inclined surface which constitutes a stop for limiting the upward displacement of the weft or filling, the said lower inclined surface being constructed and arranged to engage an improperly boxed shuttle below the junction of the upper and lower inclined surfaces.

In testimony whereof, I have signed my 110 name to this specification.

ALFRED E. STAFFORD.
